(21) Appl. No.: **29/311,992**

(57) **CLAIM**

(22) Filed: **Aug. 18, 2009**

The ornamental design for a rebar tying machine, as shown and described.

(30) **Foreign Application Priority Data**

Apr. 14, 2009 (JP) 2009-008501

DESCRIPTION

(51) **LOC (9) Cl.** **08-04**

FIG. 1 is a perspective view of the front, left side and top plan of a rebar tying machine showing my new design;

(52) **U.S. Cl.** **D8/68**

FIG. 2 is a front view thereof;

(58) **Field of Classification Search** D8/68-70;

FIG. 3 is a rear view thereof;

140/57, 93 A, 93.6, 119

FIG. 4 is a top plan view thereof;

See application file for complete search history.

FIG. 5 is a bottom view thereof;

(56) **References Cited**

FIG. 6 is a left side view thereof;
